UNITED STATES PATENT OFFICE

165,835

LAWN SEAT

Henry P. Glass, Chicago, Ill., assignor to Goshen
Manufacturing Company, Goshen, Ind.

Application October 19, 1950, Serial No. 12,628

Term of patent 14 years

(Cl. D15—11)

To all whom it may concern:

Be it known that I, Henry P. Glass, a citizen of the United States, residing at Chicago, State of Illinois, have invented a new, original, and ornamental Design for Lawn Seat, of which the following is a specification, reference being had to the accompanying drawing, forming a part hereof.

The figure is a front perspective view of a lawn seat, showing my new design.

I claim:

The ornamental design for a lawn seat, as shown.

HENRY P. GLASS.
